(57) **CLAIM**

The ornamental design for refrigerated showcase, as shown
and described.

DESCRIPTION

FIG. 1 is a front elevational view of a first embodiment of
a refrigerated showcase, showing our new design;

FIG. 2 is a rear elevational view thereof;

FIG. 3 is a left side elevational view thereof;

FIG. 4 is a top plan view thereof;

FIG. 5 is a bottom plan view thereof;

FIG. 6 is a perspective view thereof;

FIG. 7 is a greatly enlarged cross-sectional view thereof,
taken along line 7—7 in FIG. 1;

FIG. 8 is a greatly enlarged cross-sectional view thereof,
taken along line 8—8 in FIG. 1;

FIG. 9 is a front elevational view of a second embodiment
of a refrigerated showcase, showing our new design;

FIG. 10 is a rear elevational view thereof;

FIG. 11 is a left side elevational view thereof;

FIG. 12 is a top plan view thereof;

FIG. 13 is a bottom plan view thereof;

FIG. 14 is a perspective view thereof;

FIG. 15 is a greatly enlarged cross-sectional view thereof,
taken along line 15—15 in FIG. 9; and,

FIG. 16 is an enlarged cross-sectional view thereof, taken
along line 16—16 in FIG. 9.
